DESIGN FOR A FROZEN FOOD MERCHANDISING UNIT

Arthur T. Millott, Minneapolis, Minn.

Application January 11, 1946, Serial No. 125,452

Term of patent 14 years

(Cl. D80—11)

To all whom it may concern:

Be it known that I, Arthur T. Millott, a citizen of the United States, in the county of Hennepin and State of Minnesota, have invented a new, original, and ornamental Design for a Frozen Food Merchandising Unit, of which the following is a specification, reference being had to the accompanying drawing, forming part thereof.

The figure is a perspective view of a frozen food merchandising unit, showing my new design.

The unit claimed herein is of uniform appearance on all sides.

I claim:

The ornamental design for a frozen food merchandising unit, as shown and described.

ARTHUR T. MILLOTT.
